OPERATING MECHANISM FOR PLUG DOOR
 John D. Bailey, Chicago, Ill., assignor to Pullman Incorporated, Chicago, Ill., a corporation of Delaware
 Filed Aug. 26, 1963, Ser. No. 304,419
 4 Claims. (Cl. 20—23)

This invention relates to an operating mechanism for laterally movable doors of freight vehicles (such doors being commonly referred to as "plug doors"), and in particular, this invention relates to the operating mechanism disclosed in the copending application of John D. Bailey, Serial No. 96,562, filed March 17, 1961, of which this application is a continuation-in-part, now Patent No. 3,179,984 issued April 27, 1965.

The above referred to application, Serial No. 96,562 (the disclosure of which is hereby incorporated herein by this reference) discloses a single operating handle disposed on the exterior side of the door and an auxiliary door locking device disposed within the door structure. Rotation of the operating handle actuates the mechanism to move the door laterally and the door locking device operates in conjunction with the mechanism.

This application discloses means for actuating the operating mechanism from either side of the door, that is, from the interior side as well as from the exterior side and a new auxiliary door locking device is also disclosed which device is mounted on the exterior side of the door.

It is common practice in the loading and unloading operations of freight vehicles to use lift trucks for transferring the lading into and out of the vehicle and it has been found that maneuverability of the lift trucks, when in the vehicle, is made easier by having the doors open on both sides of the vehicle. Thus, when required, it is convenient to be able to open the doors on the car side opposite the loading platform from inside the car. This eliminates any need for walking around the train to open the doors from the outside which would be especially inconvenient where the car to be unloaded is located in the middle of a long train.

Accordingly, one of the objects of the invention is to provide operating mechanism for a laterally movable door having means for actuating the mechanism from either side of the door.

Another object of the invention is to provide operating mechanism for a laterally movable door which, when actuated by a single manual operation from either face of the door, moves the door laterally into and out of its door opening.

Another object of the invention is the provision of operating and locking mechanism for a laterally movable door wherein a single manual operation from either side of the door actuates the mechanism for movement of the door into and out of the door opening and the door is respectively locked and unlocked in the door opening.

Another object is to provide a laterally movable door for a freight vehicle having mechanism including a fixed actuating handle on the exterior side of the door and means on the interior side of the door for applying a loose portable actuating handle each rotatable in a plane parallel to the door wherein upon rotation of either handle in respectively opposite directions the mechanism moves the door laterally into and from the door opening and in such movements of the door one of its vertical edges is moved ahead of its other vertical edge.

A further object comprehends a laterally movable door having mechanism manually operable by means of handles, one on each face thereof and each rotatable in a plane parallel to the door wherein upon rotation of either handle in respectively opposite directions, the

2

door moves laterally into and out of the door opening and in such movements of the door, its vertical trailing edge is moved into the door opening ahead of its vertical leading edge and its vertical leading edge is moved out of the door opening ahead of its vertical trailing edge.

5 A still further object is to provide a laterally movable door for a freight vehicle having mechanism including an auxiliary locking device wherein the bottom edge of the door is locked and unlocked in the door opening sequentially with the actuation of the mechanism for respective movements of the door into and out of the door opening.

10 Still another object is to provide a laterally movable door for a freight vehicle having operating mechanism and an auxiliary locking device and the device being connected to the mechanism with follower type attachment to insure positive locking and unlocking operations of the device during actuation of the mechanism.

15 The foregoing and other objects of the invention are attained by the mechanism and arrangement illustrated in the accompanying drawings wherein:

20 FIG. 1 is a fragmentary elevational view of the side wall of a freight vehicle showing a sliding side door in closed position covering approximately one-half of the side door opening of the vehicle adjacent to a laterally movable side door applied in and covering the remaining half of the door opening and incorporating the mechanism of the invention disclosed in said application, Serial No. 96,562;

25 FIG. 2 is a vertical sectional view taken on line 2—2 of FIG. 1 showing the laterally movable door in closed position within the recessed portion of the side door opening;

30 FIG. 3 is a vertical sectional view taken on line 3—3 of FIG. 1, showing the sliding door in closed position;

35 FIGS. 4A and 4B are complementary horizontal sectional views taken on line 4—4 of FIG. 1, showing the sliding side door and the laterally movable side door in closed position;

40 FIG. 5 is a fragmentary elevational view of the laterally movable door showing the operating mechanism of the invention disclosed in said application, Serial No. 96,562, applied to the door structure with the outside sheathing and the inside lining of the door removed to more clearly show the mechanism;

45 FIG. 6 is a horizontal sectional view taken on line 6—6 of FIG. 5;

50 FIG. 7 is a vertical sectional view taken on line 7—7 of FIG. 5;

55 FIG. 8 is a vertical sectional view taken on line 8—8 of FIG. 5;

FIG. 9 shows the sliding and laterally movable side doors of FIG. 1 in full open position;

FIG. 10 is a sectional view of the edge portions of the laterally movable door of FIG. 1 showing the application of the non-metallic flexible sealing member;

FIG. 11 is a sectional view of the non-metallic flexible sealing member to a larger scale;

60 FIG. 12 is an isometric view of the channel shape bendable retainer clip used for securing the sealing member to the laterally movable door;

65 FIG. 13 is a horizontal sectional view through the vertical leading edge portion of the laterally movable door of FIG. 1 at the lower corner portion thereof showing the application of the sealing member at this point;

70 FIG. 14 is an elevational view partly in section showing the locking arrangement for the adjustable pivot pin of the roller-supporting housing;

FIGS. 15, 16, 17, 18, 19, 20, 21 and 22 show the relative positions of the cam member, cam followers and actuating handle of the operating mechanism of the invention dis-

closed in said application, Serial No. 96,562, for various lateral positions of the laterally movable door, as indicated below:

FIGS. 15 and 16—The door in closed and locked position within the recessed door opening;

FIGS. 17 and 18—The vertical trailing edge of the door remaining in the door opening and the vertical leading edge moved out approximately one-third of the full lateral movement of the door;

FIGS. 19 and 20—The vertical trailing and leading edges of the door each moved out of the door opening respectively approximately one-third and two-thirds of the full lateral movement of the door;

FIGS. 21 and 22—Both vertical edges of door moved out of door opening the full lateral movement of the door;

FIG. 23 is a fragmentary elevational view of the laterally movable door of FIG. 1 with portions of the outside sheathing broken away to show an auxiliary lock and supporting device for the vertical trailing edge of the door;

FIG. 24 is a horizontal sectional view taken on line 24—24 of FIG. 23;

FIG. 25 is a horizontal sectional view through a laterally movable door and a recessed door opening in the wall of a refrigerator freight vehicle showing the door in closed position within the door opening;

FIG. 26 is a perspective view of an inter-engaging device for the laterally movable door of FIG. 1 showing the device in engaged position;

FIG. 27 is a fragmentary horizontal sectional view similar to FIG. 24;

FIG. 28 is a fragmentary elevational view of the laterally movable door of FIG. 1 showing the operating mechanism of the invention disclosed in said application, Serial No. 96,562, applied to the door structure and incorporating the actuating means and the auxiliary locking device of this invention;

FIG. 29 is a horizontal sectional view taken on line 29—29 of FIG. 28;

FIG. 30 is an elevational view taken on line 30—30 of FIG. 29; and

FIG. 31 is a vertical sectional view taken on line 31—31 of FIG. 28.

This invention modifies the actuating handle of the inventive mechanism disclosed in said application, Serial No. 96,562, and provides means whereby the mechanism may be actuated from inside the vehicle as well as from outside the vehicle. Actuation of the mechanism from either the inside or the outside moves the door laterally into and out of a recessed door opening in the side wall of the vehicle. The mechanism is actuated by a single manual operation, and the door is locked and unlocked in the door opening sequentially with the actuation of the mechanism for respective movements of the door into and out of the door opening. In the lateral movements of the door, one of its vertical edges is moved ahead of its other vertical edge. This invention also provides an auxiliary locking device for the door which device operates in conjunction with the door operating mechanism through positive contacting arrangement provided between the device and the mechanism.

The railroad car, the laterally movable door and the operating mechanism for the door are essentially the same as described in said copending application. The novel means for actuating the mechanism and the new auxiliary locking device of this invention are shown in FIGS. 28, 29, 30 and 31 of the drawings.

In the drawings, 10 represents the side wall of a railway box car employing the usual construction including an angle section side sill 11, a channel section sub-side sill 12, a Z section side plate 13, outside sheathing 14 and inside lining 15. The side wall, as shown in FIGS. 1, 2, 3, 4A and 4B, is provided with a comparatively large-size door opening 16 and two doors, each of a different type,

are used to cover the opening, with each door covering approximately one-half of the opening.

The door 17 covering the right-hand portion of opening 16 is of the sliding type usually provided on so-called standard railway box cars. The door is disposed outwardly from the opening and side wall of the car and is supported by rollers 18 which are movably mounted on the angle section track 19 extending in parallel relationship with the side wall so that the door can be moved longitudinally from its position covering the opening to a position beyond the opening to uncover the opening, as shown in FIG. 9. The construction of the door may be in various forms. The door shown is of welded construction and includes a plurality of horizontal juxtaposed members 20 and framing members generally Z shape in section extending along the top 21, bottom 22, vertical leading 23 and vertical trailing 24 edges of the door. The door is shown equipped with the usual parts necessary for the operation of the door including a locking device 25, a door opening and closing device 26, a safety latch 27, safety stops for door closed 28 and door-open 29 positions, back stops 30 and an operating handle 51.

The door 31 covering the left-hand portion of opening 16 is of the laterally movable type which when in closed position is disposed within the side wall opening 16 so that the outside and inside surfaces of the door 31 are substantially flush with the respective outside and inside surfaces of the side wall 10. Operating mechanism designated generally by the numeral 32 is provided which, when actuated in one direction, moves the door laterally out of the door opening to a position outwardly of the opening and side wall and when actuated in the opposite direction, moves the door into the opening. By means of mechanism 32, as will later be described, the door 31 is supported by rollers 33, which are movably mounted on the bar section track 34 extending in parallel relationship with the side wall so that when the door is in the outward position it can be moved longitudinally to a position beyond the opening to uncover the opening as shown in FIG. 9.

The construction of door 31 in the form illustrated includes a built-up generally box section framing member extending along the top 35, bottom 36 and vertical trailing 37 edges of the door and a one-piece box section framing member 38 extending along the vertical leading edge. The vertical members 37 and 38 are welded at the upper and lower corners of the door to the top member 35 and the bottom member 36 respectively to provide a continuous outer frame for the door. Intermediate vertical 39 and horizontal 40 Z section stiffener members are provided which are fitted and welded at their ends to adjacent framing members. Outside sheathing 45 is secured to the framing members 35, 36, 37 and 38 and to the stiffener members 39 and 40 by welding. Wood furring members 41 are provided at and secured to the framing members 35, 36, 37 and 38 and to stiffener members 39 and 40 by bolts 42. Inside lining 43 is secured to the furring members 41 by nailing. A non-metallic flexible sealing member 44 extends along and is secured to the inside surfaces of the top, bottom and vertical trailing edge framing members 35, 36 and 37 which hereinafter will be more fully described.

The right-hand (sliding door 17) portion of door opening 16 is formed at the side by vertical box section post member 46a which extends between and is secured at its respective end portions to side sill 11 and side plate 13 by welding. Channel section header member 47 and angle section threshold member 49 form the top and bottom of the opening respectively. The header 47 and threshold 49 members are each welded at their outer ends to post 46 and extend inwardly from the post to approximately the center of the opening. The inner upstanding flange of header 47 is secured to the depending flange of side plate 13 and threshold 49 is welded to the cut-down upstanding flange of side sill 11. Generally Z

shaped section door top retainer 48 is secured to side plate 13 and extends from approximately the center of opening 16 to post 46 and beyond for the full length of the movement of the door 17 as it travels to the full open position. Door guides 50 are welded to the door top framing member 21. Sliding door stop and sealing member 52 is secured to the front face of the vertical leading edge framing member 38 of the laterally movable door. Member 52 extends vertically substantially for the full height of the doors and is formed with a channel shaped groove 53 for engagement with the leading edge of door 17 when in closed position, thereby providing a weathertight and lightproof seal between the doors. Sparks strip 54 and baffle plate 55 are secured to door post 46 and extend vertically substantially for the full height of the door. The hook portion 56 of the trailing edge of door 17 engages the formed groove of spark strip 54 and its edge surface 57 contacts the baffle plate 55 when the door is in closed position to provide a weathertight and lightproof seal at the trailing edge of the door.

The angle section door supporting track member 19 provided for door 17 is mounted on the side wall by means of brackets 58 secured to the sub-side sill 12 which space the track outwardly from and in parallel relationship with the side wall. The track 19 extends continuously from approximately the center of opening 16 to post 46 and beyond for the full length of the movement of the door as it travels to the full open position. As explained above, groove 53 of member 52 provides a front stop for door 17 which affords a limit to the maximum travel of the door to the closed position and stops 30 at the opposite end of the track and the top retainer act to limit the maximum travel of the door to the full open position.

The left-hand (laterally movable door 31) portion of door opening 16 is formed at the side by vertical Z shaped section post 59 which extends between and is secured at its respective end portions to side sill 11 and side plate 13 by welding. A similar Z section header member 61 is provided at the top of the opening extending from the door post 59 to approximately the center of the door opening. The header member has its outer upstanding flange 62 secured to the side plate 13 and its inner depending flange 63 is disposed flush with the inner flange 60 of door post 59. The header member is welded to the door post at the upper corner of the door opening to provide a continuous frame for the opening and the inner flanges 60 and 63 provide a continuous abutment at the top and side of the opening. At the bottom a member 64 extends continuously from the door post 59 to approximately the center of the opening 16. The member 64 is welded to the door post at the bottom corner of the door opening and longitudinally to the sub-side sill 12. The vertical upstanding portion 65 of member 64 is disposed flush with the inner flange 60 of door post 59 and is welded thereto. The inwardly directed flange 66 of member 64 overlies the floor of the car and affords a threshold at the opening. The abutment provided by flanges 60 and 63 of members 59 and 61 respectively and the vertical portion 65 of member 64 is disposed inwardly of the outside surface of the side wall thus to provide a recess for the reception of door 31 so that in its closed position the door may be disposed with its outside and inside surfaces substantially flush with the respective outside and inside surfaces of the side wall. At approximately the center of door opening 16 the respective inner ends of the door opening bottom members, 49 for door 17 and 64 for door 31, are welded to a connecting plate 67 transversely disposed between the ends of the members as shown in FIGS. 9 and 13 whereby a continuous bottom member is provided extending across the full width of the opening. A similar transversely disposed connecting plate 75

67A is provided at the top of the door opening in vertical alignment with plate 67. This plate joins the inner end of retainer member 48 with the inner end of retainer member 68. Retainer member 68 is secured to side plate 13 and extends longitudinally from plate 67A to post 59 and beyond for the full length of the movement of door 31 as it travels to the full open position.

The bar section door supporting track member 34 provided for door 31 is mounted on the side wall by means of brackets 69 secured to the sub-side sill 12 which space the track outwardly from and in parallel relationship with the side wall. The track 34 extends continuously from approximately the center of opening 16 to post 60 and beyond for the full length of the movement of the door as it travels to the full open position. Lugs 70 and 71 welded to the upwardly facing surface of track bar 34 and horizontal flange 72 of top retainer 68 respectively provide front stops for door 31 which limits the longitudinal travel of the door where movement is 20 in the direction of the door opening. Door stops 73 are secured to the side wall and act to limit the maximum longitudinal travel of the door to the full open position. In the full open position of door 31, the vertical leading edge 74 of the door is located beyond the side of the door 25 opening formed by post 59 so as to help protect the door and its operating mechanism from being damaged by trucks or lading during car loading and unloading operations.

The operating mechanism 32 for the laterally movable door 31 includes a pair of vertical operating shafts 75 and 76 extending the full height of the door and disposed adjacent the vertical leading and trailing edges of the door respectively. The shafts are rotatably mounted adjacent the top and bottom of each shaft in guides 77 and 78 which are secured respectively to the top and bottom framing members 35 and 36 on the outside surfaces thereof. A third guide 79 is provided for each shaft located between guides 77 and 78 in the lower portions of the shafts as best shown in FIG. 1. At the top and bottom 40 of each shaft is a horizontally disposed crank arm 80 and 81 respectively. The arms are each integrated with their respective shafts by welding and the top arms 80 are disposed above the top edge of the door and bottom arms 81 below the bottom edge which permits the door to pass 45 between the arms during lateral movement into and out of the door opening. In the closed position of the door each pair of arms on each shaft is angularly directed toward the vertical center of the door forming equal acute angles with respect to the outer surface of the door. Adjacent the outer end of each top arm 80 is an upstanding pivot pin 82 fixedly secured to the arm and pivotally secured to a door guide shoe 83 which is slidably mounted in the retainer member 68. The guide shoe 83 has an outwardly facing surface 84 and a downwardly facing 55 surface 85 which being in slidable contact with depending flange 86 and horizontal flange 72 of retainer 68 respectively guides the pivot pin 82 with respect to the side wall of the car and directs the top of the door during longitudinal movement. Adjacent the outer end of each bottom arm 81 is a recess 87 by which the arm is pivotally mounted on the pivot pin 88 of the roller-supporting housing 89.

Two vertically disposed rollers 33 are pivotally mounted in each housing 89 by means of pivot pins 90. The housing lugs 91 extending downwardly on each side of track bar 34 guide the rollers 33 and pivot pin 88 with respect to the track bar and side wall of the car and direct the bottom of the door during longitudinal movements. Each pivot pin 88 has a threaded lower portion 92 which screws into a vertical threaded hole 93 provided in the boss portion 94 of housing 89 as best shown in FIG. 14. A hexagon head 95 is provided at the lower end of pin 88 for turning the pin in hole 93 to adjust the height of the pin which, in turn, adjusts the height of the door through the lower arms 81 and shaft guides 78. The

pins 88 support the arms 81 at their top ends 96 and the shoulder surfaces 97 provided at the tops of arms 81 support the lower shaft guides 78. A self-locking arrangement is provided for holding pivot pin 88 in an adjusted height position which, as illustrated in FIG. 14, comprises a series of inclined holes 98 extending inwardly and upwardly (approximately 45°) in the boss portion 94 of housing 89. Non-metallic flexible inserts 99 are applied in the holes 98 with the inside ends of the inserts in contact with the threaded portion 92 of pin 88. The inserts being flexible form tight fitting threads around the pin and prevent it from turning without the use of external force as may be obtained by the use of a wrench applied to the head portion 95 of the pin. The angle at which the inserts are applied provides a support to resist back-out of the inserts from their holes, thereby providing a positive lock for the pivot pin.

The arms 80 and 81 are equal in length extending from the center point of shafts, 75 and 76, to the center point of each pivot pin, 82 and 88, so that each pair of pins (82 and 88) for each shaft is in vertical alignment with each other and provide hinging points for door 31 for movement into and out of the door opening 16.

The operating mechanism 32 further includes a pair of horizontal operating rods 100 and 101 extending in respectively opposite directions from an operating cam member 102, which is centrally located on door 31, to the shafts 75 and 76. Rods 100 and 101 are pivotally secured by means of vertical pin 105 adjacent their outer ends to connecting arms 103 and 104 respectively. Connecting arms 103 and 104 are each integrated with their respective operating shafts 75 and 76 by welding. The inner end portion of each operating rod is inwardly directed toward door 31 as at 106 for rod 100 and 107 for rod 101. The end portions 106 and 107 extend through their respective horizontal guide slots 108 and 109 provided in guide member 113 and have inwardly directed cam followers 110 and 111 mounted on their respective inner end surfaces. The cam followers engage cam slots provided in the operating cam member 102 which hereinafter will be more fully described.

At the center of door 31 is an outer face plate 112, which, together with guide member 113, forms a base member for supporting the door operating mechanism. The plate extends between the vertical stiffeners 39 and is welded thereto as best shown in FIGS. 5, 6, 7, 28 and 29. The guide member 113, which provides the guide slots 108 and 109, is applied through matched openings in the face plate 112 and the outside sheathing 45 and is welded thereto as indicated. The end portions 106 and 107 of rods 100 and 101 are slidable in the respective slots 108 and 109, whereby the slots serve to guide and restrict the movement of the operating rods to axial or horizontal movement during lateral movements of door 31 into and out of door opening 16.

The operating cam member 102 is vertically disposed in the enclosure or cam pocket 119 which is formed by the outer face plate 112 and guide member 113 and the inner pan shaped housing member 116. The housing member 116 is welded to the face plate 112 along the edges of the flanges of the housing, as indicated at 117. At the inner end portion of each operating rod 100 and 101 is an integral flat vertical portion 114 and 115 adjacent slot openings 108 and 109 respectively which serve as covers for the slot openings when door 31 is in closed position to prevent snow, ice, dirt and other foreign matter from entering the cam pocket 119 through the slot openings, as best shown in FIGS. 6 and 29. In FIGS. 28 and 29 horizontal lug 250 and vertical lug 251 extend from flat portion 114 and rod 100 to form a part of the door seal arrangement of this invention which hereinafter will be more fully described. Hole 120 at the center of door 31 adjacent the bottom of cam pocket 119 extends through the outside sheathing 45 and the face plate 112 and serves as a drainage hole for any moisture which may filter into the cam

pocket. Cam member 102 is circular in shape and has a horizontal pivot pin 118 in FIGS. 5, 6 and 7 and 252 in FIGS. 28, 29 and 30 fixedly secured at its center. The pins 118 and 252 being substantially in normal alignment with the surfaces of the member extend through the member with their inner and outer end portions extending outwardly from the respective sides. The inner end portion of pin 118 is pivotally mounted in bearing 121 which is secured to the inside surface of the web portion of housing 116. The outer end portion of pin 118 is pivotally mounted and extends through bearing 122 which is provided in guide member 113. At the outer end of pin 118 is a yoke member 123 which is fixedly secured to the pin and is provided with a clevis at its outer end. The operating handle 124 of the mechanism is pivotally secured to the clevis by means of pivot pin 125 so that the operating handle can be swung 180° in an arc normal to the outside surface of the door with the operating handle in any of its several operating positions.

The inner end portion of pin 252 is formed to provide a circular head pivotally mounted in bearing 253 which is secured to the inside surface of the web portion of housing 116. A square-sided recess 254, which serves as a socket, is provided in the inner head of pin 252. A commercial portable ratchet type wrench having a square section bit inserted into socket 254 is indicated in phantom lines 255. It can be seen that this wrench or other suitable type handle may be used to rotate cam member 102 which in turn actuates the mechanism to move the door into and out of the door opening as will later be more fully described. It should be noted that the inside surface of pin 252 is flush with the inside surface of the door so that there is no projection into the car at this point. Also it is understood that while the inner head of pin 252 is disclosed as a square-shaped socket type the socket may be of other shapes such as hexagon and the head may be of another type such as square or hexagon type in which event the wrench bit would be a socket type. The outer portion of pin 252 is pivotally mounted and extends through bearing 256 which is provided in guide member 113. Actuating handle 257, forming a T type handle, is fixedly secured to pin 252 adjacent bearing 256 and threaded holding member 258 is applied over the threaded end portion of the pin adjacent handle 257. Extending inwardly and downwardly from handle 257 on the right hand side thereof is a vertical flange 259. This flange is in proximate relation with lug 251 of rod 100 and horizontally aligned holes 260 are provided in the lug and flange through which the car seal is applied. Thus it can be seen that the door operating cam member 102 can be rotated from outside the vehicle by rotating movement of handle 257 or from inside the vehicle by rotating movement of removable wrench or handle 255. It should be noted that in the opening operation of the door the mechanism is actuated by rotating handles 257 or 255 in counterclockwise direction when viewing the door from the outside and in the event the door is to be opened from inside the car with the car seal still intact, the seal will be broken by the shearing action between flange 259 and lug 251 when handle 257 is rotated due to the rotation of wrench 255.

As shown in FIGS. 15, 17, 19 and 21, the operating cam member 102 is provided with two cam slots 126 and 127, having contours shaped differently from each other. The cam slots are engaged by cam followers 110 and 111 as indicated. In the operation of the mechanism, cam member 102 is manually rotated by means of operating handles 124 or 257 or wrench 255 through their respective center pivot pins 118 or 252 which are pivotally mounted in bearings as described above. It is obvious that slots 126 and 127 also rotate with the rotation of the cam member so that the horizontal distances between the center of the cam member pivot pin and the centers of the cam slots on each side thereof are changed progressively during rotation. In this operation the cam followers are directed by the slots to move in respectively opposite directions and sim-

ilarly the distances between the center of the cam member pivot pin and the centers of the cam followers are changed progressively and also during rotation of the cam member one cam follower moves ahead of the other due to the shape and arrangement of the slots.

Reference is now made to FIGS. 15 and 16 wherein certain parts of the mechanism are shown in their relative positions when door 31 is closed and locked within the recessed door opening 16. In this situation, the cam followers 110 and 111 are located at equal minimum distances from the cam member pivot pin on each side thereof and the inner ends of slots 126 and 127 are in contact with the followers. This locks the mechanism since there can be no horizontal movement of the followers without rotation of the cam member. In the closed position of the door, the operating handle 124 is put into a retainer member 128 which is secured to the outer face of the door and supports the handle as indicated in FIG. 16. The retainer is channel shaped in section having generally upwardly extending flanges and a web portion supporting the handle. A sealing member 129 in the form of a pawl is provided at the top of the retainer which is pivoted at its top so that it may be swung counterclockwise to an upper position for removing the operating handle from the retainer and clockwise to a lower position when the handle is in the retainer. Stops are provided for holding the seal member in its upper and lower positions and an outwardly extending flange is provided on the seal member and on the retainer with a matching hole extending through the two flanges for the insertion of a seal. A similar retainer member 130, but without a sealing member, is provided oppositely to retainer 128 for holding the operating handle when the door is in the open position, as shown in FIG. 22. It should be noted that the force or direction of movement of the handle in the retainers is downward in both cases, that is, in the actuation of the mechanism to open the door the operating handle is rotated counter-clockwise and to close the door the handle is rotated clockwise. This arrangement helps to keep the operating handle in place in the retainers and when the door is in the closed position, it relieves pressure from the car seal so that it will not be sheared off. It should be pointed out that the foregoing with respect to the operating handle retainers and the car sealing arrangement does not apply to handle 257 which has a different car sealing arrangement as hereinbefore described.

Starting with the door in closed and locked position in the door opening, the mechanism is actuated for moving the door laterally out of the opening by (operating handle 124 is first removed from the retainer 128) rotating the handle counter-clockwise. Rotation of the operating handle rotates the cam member 102 and cam slots 126 and 127 in the same direction. At their inner ends both slots are circular shape about the cam member pivot pin to provide a small dead travel portion wherein there is no horizontal movement of the cam followers, as indicated by the dot and dash lines in FIGS. 15 and 16. Thus the door is locked in closed position and it cannot be moved outwardly until after the cam member has been rotated beyond the dead travel portion of slot 126 and the operating portion of the slot is engaged by follower 110. These dead travel portions of the cam slots prevent rotation of the cam member from any forces or loads that might be imposed upon the door from the sealing arrangement or lading until after the cam member has been actuated by the handle. The dead travel portion at the inner end of slot 127 is greater than that of slot 126 which will later be described. As the cam member and slots continue to rotate counter-clockwise, the cam slots direct the cam followers to move them outwardly on each side from the cam member pivot pin and since the followers are mounted on the inner end portions of the operating rods 100 and 101, the rods are likewise moved accordingly. This movement of the operating rods causes swinging move-

ment to the connecting arms 103 and 104 and rotation to the operating shafts 75 and 76 with respect to the door through their respective guides 77, 78 and 79. The rotation of the shafts causes the crank arms 80 and 81 to swing about the pivot pins 82 and 88 at the top and bottom of each shaft respectively which, in turn, moves the door laterally out of the door opening. The mechanism operates in the same manner except that the parts move in reverse direction when the door is moved laterally into the door opening in which case the operating handle is (operating handle 124 is first removed from the retainer 130) rotated clockwise.

One of the important features of the mechanism whereby one vertical edge of the door is moved ahead of the other vertical edge is best described by reference to FIGS. 15 to 22 which show the relative positions of the cam member 102, including the cam slots 126 and 127, the cam followers 110 and 111, and the operating handle 124 for various lateral positions of the door 31. When operating handle 257 and wrench 255 are used their angle of swing for various positions of the door would be essentially the same as indicated for handle 124. As discussed above, FIGS. 15 and 16 show the parts of the mechanism in position when the door is closed and locked within the recessed door opening and in this situation, the cam followers 110 and 111 being aligned in horizontal plane with the cam member pivot pin are at equal distances on each side of the pin. FIGS. 17 and 18 show the parts in position after handle 124 and cam member 102 have been rotated counter-clockwise approximately 103° from their original positions in FIGS. 15 and 16. It can be seen that during this rotation cam slot 126 has directed follower 110 to a new position outwardly from its original position in FIG. 15, while follower 111 has remained in the same position due to the dead travel portion DT provided at the inner end of cam slot 127, as indicated in FIG. 17. Up to this point in the rotation, only the right-hand part of mechanism 32 has been actuated by the outward horizontal movement of follower 110. This partial operation of the mechanism has caused the leading edge 38 of door 31 to be moved laterally out of the door opening for a distance equal to approximately one-third of the full lateral movement of the door, but since there was no movement of follower 111 to actuate the left-hand part of the mechanism, the trailing edge 37 of the door remains in the door opening. In FIGS. 19 and 20, the operating handle and cam member have been rotated counter-clockwise approximately 180°, and here it can be seen that follower 110 has been directed to a new position outward from its position in FIG. 17 and follower 111 now being engaged with the operating portion of slot 127 has also been directed outwardly to a new position in the opposite direction. This outward movement of follower 111 has actuated the left-hand part of mechanism 32 which has caused the trailing edge 37 of the door to be moved laterally out of the door opening. At this point, the leading 38 and trailing 37 edges of the door have been moved out of the door opening to distances equal to approximately two-thirds and one-third of the full lateral movement of the door respectively. In FIGS. 21 and 22, the operating handle and cam member have been rotated counter-clockwise approximately 273°, which constitutes the full rotation necessary to direct the followers to their respective maximum outward positions on each side of the cam member pivot pin as indicated. During this final stage of the operation, both the right-hand and left-hand parts of the mechanism continue to move the door outward until both door edges 38 and 37 have been moved to the full outward position of the door whereby the door is then in position outside of and parallel to the side wall of the vehicle so that the door can be moved longitudinally to uncover the door opening. During the full rotation of the cam member to move the door outward,

the dead travel portion DT provided at the outer end of cam slot 126, as indicated in FIG. 21, allows the outward horizontal travel of follower 111 to catch up in distance to follower 110 and this, in turn, allows the door to straighten out so as to be in parallel relationship with the side wall of the vehicle.

Thus, from the foregoing, it can be seen that when the mechanism is actuated to move the door laterally out of the door opening by manual counter-clockwise rotation of the operating handle, the leading edge 38 of the door moves ahead of the trailing edge 37. It is quite obvious then that when the mechanism is actuated to move the door laterally into the door opening by manual clockwise rotation of the operating handle, the mechanism operates in reverse so that the trailing edge 37 of the door moves ahead of the leading edge 38.

As explained above, the operating handle 124 is pivotally connected to pivot pin 118 by means of a clevis secured to the outer end of pin 118 and pin 125. The handle then can be swung 180° in an arc normal to the outside surface of door 31 as indicated in FIG. 22 wherein the dot and dash lines indicate the position of the handle after it has been rotated counter-clockwise 273° from its position where the door is in the door opening (FIG. 16) to its position when door is out of the door opening (FIG. 22). The full lines show the handle after it has been swung downward 180° and placed in the retainer member 130. The handle may be swung 180° to the opposite side of pivot pin 118 regardless of the angular position of the handle which provides a means whereby the full rotation of the handle can be made in either of the respective areas extending above or below the horizontal plane formed by the horizontal operating arms 100 and 101. An example of this operation is best described by referring to FIG. 20 wherein the handle is shown extending in an upward direction to show the 180° counter-clockwise rotation of the handle. The handle in this case could have been stopped in its rotating movement when it reached a horizontal position on the right side of pin 118 and then swung over to the left side of the pin to continue and complete its full counter-clockwise rotation below the horizontal plane. This is an important feature since it provides for easier operation of the door when the operator is standing on the ground level.

In the arrangement described above wherein the laterally movable door 31 is used in combination with the sliding door 17, the leading edge framing member 38 of door 31 serves as a door post for the leading edge 23 of door 17. The vertically disposed auxiliary locking bar device 131, shown in FIG. 1, aids member 38 in this respect by securing it directly to the car structure at the top and bottom thereof. The locking device comprises a lower locking bar 132 which is slidably mounted in guides 135 and 137 secured to the outside surface of the door and an upper locking bar 133 which is also slidably mounted in guides 135 and in guide 139 which is likewise secured to the outside surface of the door. The operating handle 134 is pivotally secured to the door at 136 and to the locking bars 132 and 133 at 142 and 141 respectively so that when the handle is moved upward the lower bar 132 and the upper bar 133 are moved downwardly and upwardly respectively with their end portions being extended to engage keeper members 138 and 140 respectively. Keeper members 138 and 140 are secured to the car structure as shown in FIG. 1. Thus the locking bars in their engagement with the keeper members provide an auxiliary lock for the door when in closed position, as well as a supporting means for door member 38 to resist any horizontal forces that might be applied against the member. When the handle is moved downwardly the movement of the locking bars is reversed and their end portions are retracted from the keeper members to unlock the door. A pivoted pawl-like gravity catch 143 is provided which, having an inwardly directed flange,

supports the lower end of the upper bar 133 in its locked position and thereby prevents both bars 132 and 133 from disengagement with the keeper members 138 and 140. The catch 143 may be swung out of the way when the handle is to be operated to disengage the locking bars.

The leading edge framing member 38 of the door 31 is further secured to the car structure by the inter-engaging device 187 located at the lower leading edge corner of the door. The device, as best shown in FIG. 26, comprises a plate member 188, the top portion of which is disposed against and secured to the outside surface of the door. The lower portion of the member projects below the bottom edge of the door and a horizontal slot 189 is provided in the member adjacent the lower edge thereof. The downwardly directed vertical flange 191 of angle member 190 is disposed against and secured to the outside surface of the sub-side sill channel 12, thereby securing the angle member to the car structure. The angle member is disposed on the side sill member in vertical and horizontal alignment with slot 189 of member 188 so that when the door is in closed position the outwardly directed horizontal flange 192 of angle member 190 engages the slot thereby preventing relative vertical movement of the door within the door opening at the leading edge thereof. At the top, bottom and opposite trailing edges, the door is prevented from such vertical movement by the sealing contacts made between the sealing members 44 and the abutment surfaces 63, 65 and 60 of the door opening framing members as will be hereinafter more fully described. Engagement and disengagement of flange 192 with slot 189 is made automatically during the respective movement of the door into and out of the door opening.

Railway box cars are used to some extent for hauling grain and other types of bulk commodities. This includes the use of box cars having the two-door combination of a laterally movable side door and a sliding side door as described herein in which case only the sliding door is used in the car loading and unloading operations. The laterally movable door remains in its closed position within the door opening and serves as additional side wall area to support the lading. Due to compactness, such types of lading produce substantial horizontal loads which are imposed upon the door, especially in the lower portion of the door. To help resist such loads and prevent outward bulging of the door, an auxiliary lock and supporting device is provided, as shown in FIGS. 23 and 24. This device operates in conjunction with the door operating mechanism 32 and requires only a slight modification to the cam member 102 comprising the addition of lug 144 to its outer edge as shown in FIG. 23. The device consists of the operating bar 145 which is located within the door in the space between the outside sheathing 45 and the inside lining 43. The bar is disposed in horizontal alignment with the center pivot pin 118 of cam member 102 and extends to the left of the cam member as indicated. Starting at its right end and extending to the left, the bar 145 first passes through hole 154 provided in the web of the vertical door stiffener 39 and then through hole 155 provided in the vertical web portion of the channel-shaped member 152. The ends of the horizontal flanges of member 152 are welded to stiffener 39 and they, together with the web portions of member 152 and stiffener 39, form a housing enclosing the compression coil spring 151 which is applied over bar 145. Spring 151 is held in place between the web portion of member 152 and a washer type stop 153 which is welded to the bar 145. Continuing to the left, the bar 145 passes through hole 146 provided in furring strip 41 and in the first adjacent web portion of the door trailing edge framing member 37 and then through hole 148 provided in the second web portion of framing member 37 and in the bar bearing member 147 which extends between and is welded to the outwardly directed flanges of framing member 37 and to their connecting web. FIGS. 23 and 24

the door is in closed position within the door opening. In this position, bar 145 extends through and projects beyond hole 149 provided in the web portion of car door post 59 which acts as a keeper for bar 145 when in locked position. The cap type member 150 is welded to the web and outer flange of post 59 to form a pocket to receive the left end portion of bar 145. As noted above, the locking and supporting device is shown in locked position in FIG. 23 in which case the door 31 is in closed position as indicated by the position of cam member 102. The right end surface of bar 145 is in contact with the outer edge surface of lug 144 and the left end portion of bar 145 extends through the keeper hole 149. Contact between bar 145 and cam member 102 is maintained by compression spring 151 which in the locked position is deflected under load, as indicated by the position of washer support 153. When the cam member is rotated counterclockwise to open the door, the lug 144 is moved out of horizontal alignment with bar 145 and the bar is moved to the right due to the load on spring 151 and the washer stop 153 is moved to the right, as shown in dot and dash lines at 153A. The rod is moved with its right end surface in contact with the curved edge surface of the cam member, as shown in dot and dash lines at 145A. The dot and dash lines at 144A indicate the position of lug 144 when the door is in full lateral open position; the cam member having been rotated 273° as hereinbefore described. The left end portion of bar 145 is, of course, retracted from keeper hole 149 with the rightward movement of the bar and the device is then in the unlocked position. It is easily perceived that the device operates in reverse to return to its locked and supporting position, as shown in FIGS. 23 and 24, when the cam member is reversely rotated clockwise to close door. As hereinbefore described, the locking bar arrangement 131 provides additional supporting means to resist horizontal loads at the leading edge of the door.

The sealing arrangement for the laterally movable door 31 functions in conjunction with the operating mechanism 32 and being compressible, it seals the door when the door is in closed position within the door opening. The arrangement comprises a non-metallic flexible sealing member 44 which, as shown in FIGS. 2 and 4A, extends along the top, bottom and trailing edges of the door. As best shown in FIG. 10, sealing member 44 is secured to the inside surfaces of the door framing members 35, 36 and 37 by means of retainer clip 156. As viewed in FIG. 11, the sealing member 44 comprises a flat top sealing portion 157 which is connected at each end to respectively opposite upper side portions 158. The upper side portions 158 each extend outwardly and downwardly from the top sealing portion to juncture points 159 located midway between the top and bottom surfaces of the member. The lower ends of each upper side portion 158 are connected to lower side portions 160, each of which extend inwardly and downwardly therefrom and are connected at their respective lower ends to the outwardly directed base flanges 161. Thus the upper 158 and lower 160 side portions form oppositely outwardly directed obtuse angles with each other at the juncture points 159. The top portion 157 is preferably formed with a serrated top surface 162 to provide a weathertight and lightproof seal when in contact with the door opening framing members. As clearly illustrated in FIG. 11, the lower side portions 160 are each formed with a thickness varying in size from minimum at juncture point 159 to maximum at lower juncture point 163 to flange 161, thereby providing enlarged heels at the feet or base of the section.

The retainer clip 156 which is used to secure sealing member 44 to the door is illustrated in FIG. 12. The clip is generally channel shape in section, with the web portion 164 serving as the base. A plurality of inner spacer flanges 165 are provided at longitudinally spaced inter-

vals in the web portion 164. The flanges 165 are formed from material obtained by cutting slots 166 in web 164. The slots are formed by first cutting the web material at side 169 and ends 170 and then bending the material upward at 171 to form flange 165. The upper portions 168 of the outer upwardly directed flanges 167 are bent inwardly forming sloping, bendable portions as indicated. The retainer clip 156 is first applied to the door edge framing members 35, 36, and 37 in the form as shown in FIG. 12 extending substantially for the full length of the members and is secured thereto by welding. The sealing member 44 is then inserted into the retainer clip 156 with flanges 161 fitted in place on respectively opposite sides thereof between the inner flanges 165 and outer flanges 167. The upper sloping portions 168 of flanges 167 are then bent down over the outer portions of flanges 161 to securely hold the sealing member in place, as shown in FIG. 10. This method of securing the sealing member to the door is more feasible and economical than other methods sometimes employed wherein holes are required in the framing members of the door for application of fasteners, or wooden strips are provided in the door framing for nailing the sealing members.

From the foregoing, it can be seen that the sealing member 44 is pantograph shape in section and is applied to the door with the top surface projecting beyond the inside surface of the door so that the member is subjected to considerable deflection when the door is in closed position as clearly shown in FIGS. 2 and 4A. The flat serrated top surface of the members provides a good sealing surface for contact with the metal abutment formed in the framing of the door opening, so that a weathertight and lightproof seal is provided between the door and door opening framework when the door is in closed position. The outside obtuse angles of the sealing members provided at 159 locate the position of the creasing points of the members during deflection, which may be noted in FIGS. 2 and 4A. This feature helps retard fatigue and deterioration of the material by repeated flexing. The enlarged heels at the feet or base of the member provide for a high degree of spring back to return the member substantially to its original shape when the door is in the open position out of the door opening which helps to minimize permanent set of the member.

As described above, the sealing member 44 is provided along the top, bottom and trailing edges of the door. The trailing ends of the top and bottom members are joined to the respective top and bottom ends of the trailing edge member to form one continuous sealing member extending around the three edges of the door. The top and bottom members terminate at the leading edge of the door as illustrated in FIG. 13. While FIG. 13 is actually a horizontal sectional view through the lower corner portion of door 31 and shows the arrangement of the door and the bottom members 49 and 64 of the door opening at this point, the drawing also applies to the respectively opposite upper corner portion of the door and the header members of the door opening which are similarly arranged so that the end portions of the top and bottom sealing members are applied in the same manner. As indicated, the lower outer portion of the leading edge framing member 38 is coped out horizontally from the vertical leading surface 74 to points 172 and 173 of the outer and inner portions of the member respectively and vertically from the bottom edge of the member to a point above to provide sufficient space for the application of the sealing member 44 and retainer 156. A plate 174 extending between the vertical cutoff points 172 and 173 and the bottom edge of the member to the horizontal cutoff point above is welded in place as indicated. Retainer 156 and sealing member 44 extend around the supporting surface formed by plate 174 with the retainer secured thereto and terminating against the inside surface of the sliding door stop and sealing member 52. A filler member 175 is welded in place in the corner pocket formed by

connecting plate 67 and the vertical portion 65 and lower horizontal portion of the bottom door opening member 64. Filler member 175 is angular in form, having a top horizontal flange 176 and downwardly extending vertical flange 177. Horizontal flange 176 is fitted into a coped-out portion of flange 66 of door opening member 64, so as to be flush with the top surfaces of flanges 66 and 49. The flange 177 is disposed in spaced parallel relationship with plate 174 and being the same height as the vertical portion 65 of the door opening framing member 64 provides a continuing contacting surface for the sealing surface 162 of sealing member 44 when the door is in closed position. Thus a weathertight and lightproof seal is provided at the top and bottom edges of the door at the leading edge thereof.

Laterally movable doors are used to a great extent on railway refrigerator cars, but in this service, only one door is used for each door opening and the doors must effectively seal the complete opening when they are in closed position to prevent loss of refrigeration through leaks around the edges of the doors. These doors are insulated like the car bodies and because of their lateral movement into the door openings to closed position, they are sometimes referred to as "plug doors." Such a door is illustrated in FIG. 25, which is a fragmentary horizontal sectional view through the door opening of a railway refrigerator car and shows door 178 in closed position within the recessed opening so that the inside and outside surfaces of the door are substantially flush with the respective inside and outside surfaces of the wall of the car. The construction of door 178 is like that of door 31 as shown in FIGS. 1, 2, 4A and 4B except that the framing member 182, wood furring strip 183 and fasteners 184 at the leading edge of the door are like the framing member 37, wood furring strip 41 and fasteners 42 at the trailing edge. The outside sheathing 179 and inside lining 180 is like the outside sheathing 45 and inside lining 43 of door 31. The intermediate stiffeners and supporting members shown in FIGS. 4A, 5, 6, and 7 are provided in door 178 and the operating mechanism provided is like that of door 31, as shown in FIGS. 1, 2, 4A, 4B, 5, 6, 7 and 15 to 22 inclusive, including the longitudinally disposed upper door guideway and retainer and the lower door track bar each of which is secured to the outside surface of the wall of the car. Insulation 187, which is like insulation 181 in the body of the car, is provided in the space between the outside sheathing 179 and inside lining 180 of the door.

The door opening framing for door 178 is like the door opening framing for door 31 except that Z section door post 185 is provided at the leading edge of the door which is like door post 59 provided at the trailing edge. The top 61 and bottom 64 framing members of the door opening extend between and are secured at their respective ends to posts 59 and 185 to form a continuous frame around the door opening. The flange 63 of top member 61 and vertical portion 65 of bottom member 64 are disposed flush with the inner flanges 60 and 186 of door posts 59 and 185 respectively to provide a continuous abutment for the door and are disposed inwardly of the outside surface of the wall of the car, thereby providing a recess for the reception of the door. Sealing member 44 is applied to the leading edge member 182 of door 178 by means of retainer 156 in the same manner as at the top, bottom and trailing edges and the top and bottom ends of the sealing member are joined to the respectively leading ends of the top and bottom sealing members to form one continuous sealing unit extending along the four edges of the door.

The operation of door 31 to close and lock the door and to unlock and open the door, as hereinbefore described also applies to door 178 since the operating mechanism of door 178 is like the operating mechanism of door 31. It should be pointed out that plug door 178 can be made to move laterally and longitudinally in a reverse manner from door 31 by the simple expedient of applying the cam member 102 in turn-around position.

This reverses the arrangement of the cam slots 126 and 127 so that clockwise rotation of the cam member moves the door out of the door opening with the vertical edge 37 moving ahead of vertical edge 182 and the vertical edge 37 then becomes the leading edge of the door. Counter-clockwise rotation of the cam member moves the door into the door opening with the trailing edge 182 moving ahead of the leading edge 37. In this situation the retainer members 128 and 130 for holding the operating handle 124 in position are reversed with respect to their location on the door and the bar section track member 34 extends to the right of the door opening so that when the door is in the outward position it can be moved longitudinally to the right of the door opening to uncover the opening which is the usual practice for single sliding doors on freight vehicles.

An auxiliary locking and supporting device is provided for door 178 which is similar to the device provided for door 31 except that it includes double horizontal locking bars 193 and 194 as shown in FIG. 27. Like the device of door 31, this device operates in conjunction with the door operating mechanism 32. The bars 193 and 194 are disposed in horizontal alignment with the center pivot pin of cam member 102 and extend in respectively opposite directions on each side of the cam member. Bar 193 in its extended or locked position engages a keeper hole provided in post member 59 and bar 194 a keeper hole in post member 185. Like bar 145, each bar 193 and 194 is provided with a spring device for retracting the bars during rotation of the cam member to move the door out of the door opening. Lugs 195 and 196 are provided on the cam member in respectively opposite offset positions as indicated to clear the opposite locking bar during rotation of the cam member. Followers 197 and 198 are pivotally mounted on the respective inner end portions of the rods 193 and 194. These followers contact their respective lugs 195 and 196, which are the same shape as lug 144, during rotation of the cam member to move the door into the door opening and thereby the bars are moved to their respective extended positions engaging the keeper holes in the respective post members. In their retracted positions the inner ends of the bars contact the outer edge of the cam member as indicated in dot and dash lines at 199 and 200.

The auxiliary locking device of this invention as shown in FIGS. 28 and 31 comprises a vertical locking member having a circular bar upper portion 261 and a rectangular section latch portion 262. Upper portion 261 and latch portion 262 are slidably mounted on the outer face of door 31 by means of guide members 263 and 264 respectively. Keeper member 265 is secured to the car structure adjacent the bottom of the door opening and engages the latch portion 262 when the locking member is extended in locking position as indicated in FIGS. 28 and 31. Adjacent the top edge of bar portion 261 is horizontal circular piece 266, said piece being secured to said bar and extending inwardly through slotted hole 267 provided in door sheathing 45 and base plate 112. Pivotally mounted on the inner end portion of piece 266 is a roller type follower 268 which engages groove 269 provided in the modified form of cam follower 102 as shown in FIGURES 28, 29, and 31 to co-operate with the locking member. A compression spring 270 is disposed in guide member 263 around bar 261 between the bottom plate 271 of the guide and plate 272 which is secured to bar 261 so as to move vertically with vertical movements of the bar. Plate 273 forms the top of guide member 263 to provide a housing for spring 270. It will be noted that the sides of groove 269 are circular shape on the right side when viewing the groove in FIG. 28 thereby forming a closed end groove. The sides of the groove extending from the closed end slope generally upwardly and the opposite end of the groove is open.

During rotation of cam member 102 in counter-clockwise

direction to open the door, the follower 268 is directed by groove 269 which, being formed with an upward direction, raises the follower which, in turn, raises the sliding locking member and thereby retracts the latch portion 262 from the keeper 265 to release the lock. In this action the groove portion 269 of the cam member 102 is rotated to the position indicated by phantom lines 274 in FIG. 28. The slotted hole 267 allows piece 266 and follower 268 to move upward and since the main outer edge of the cam member 102 does not contact the follower 268 in its upward position the compression spring 270 expands to hold the locking member in its upward position. In the reverse clockwise rotation of cam member 102 to close the door the follower 268 enters groove 269 at its open end which forces the latch portion 262 into keeper 265 to lock the door.

From the foregoing it can be seen that this invention provides novel means whereby an operating mechanism for laterally movable doors of freight vehicles may be actuated from the inside of the vehicle as well as from the outside. The actuating means provided on the inside of the vehicle does not extend beyond the inside face of the door so that there are no projections extending inwardly which might interfere with the lading. An auxiliary door locking device is provided which operates in conjunction with the door operating mechanism and novel follower type attachment is provided between the device and the mechanism which insures definite connection for positive automatic operation of the device with the operating mechanism.

What is claimed is:

1. In an actuating mechanism for a laterally movable door of a vehicle door opening, said mechanism including a pair of vertical shafts rotatably mounted on the door adjacent the respectively opposite vertical edges thereof for mounting said door upon the side of the vehicle for lateral movement and rod connecting arms secured to said shafts, said door having a transverse horizontal pivot bearing intermediate said shafts and a pair of oppositely extending guide slots disposed in horizontal alignment on each side of said bearing, a cam member disposed inwardly of the guide slots and within said door having a pivot pin rotatably mounted in said pivot bearing, said pivot pin having an inner pivot end extending through said door to the inner side of said door, the inner pivot end being substantially flush with the door inner sides and having a handle receiving means, said cam member having a pair of cam slots oppositely disposed around said pivot pin, a handle secured to said pivot pin of said cam member at the outer side of said door for imparting rotation to said cam member, said handle receiving means of the inner pivot end being adapted to receive a removable handle for engaging within said recess of guide slots and said pivot pin at the inner side of said door also for imparting rotation to said cam member, a pair of oppositely extending rods outwardly of said cam member having follower means at their respective inner ends engaging said guide slots and said cam slots and pivotally secured at their respective outer ends to said arms, said cam slots and said guide slots effecting horizontal movement of said rods during rotation of said cam member from either the inner or the outer side of said door to impart swinging movement to said arms and thereby rotate said shafts to move the door into and out of said door opening.

2. In an actuating mechanism for a laterally movable door of a vehicle door opening, said mechanism including a pair of vertical shafts rotatably mounted on the door adjacent the respectively opposite vertical edges thereof for mounting said door upon the side of the vehicle for lateral movement and rod connecting arms secured to said shafts, said door having a transverse horizontal pivot bearing, intermediate said shafts and a pair of oppositely extending guide slots disposed in horizontal align-

ment on each side of said bearing, a cam member disposed within said door having a pivot pin rotatably mounted in said pivot bearing, said pivot pin extending through said door to the inner side of said door, said cam member having a pair of cam slots oppositely disposed around said pivot pin, a handle secured to said pivot pin of said cam member at the outer side of said door for imparting rotation to said cam member, a removable handle engaging said pivot pin at the inner side of said door, also for imparting rotation to said cam member, a pair of oppositely extending rods having follower means at their respective inner ends engaging said guide slots and said cam slots and pivotally secured at their respective outer ends to said arms, said cam slots and said guide slots effecting horizontal movement of said rods during rotation of said cam member from either the inner or the outer side of said door to impart swinging movement to said arms and thereby rotate said shafts to move the door into and out of said door opening, the handle secured to the pivot pin of said cam member comprising a bar member disposed outwardly from said rods in parallel relation to the outer side of said door, and said bar member being secured midway between its ends to said pivot pin, said pivot pin of said cam member comprising an upset inner end portion having a flat inner end surface disposed in flush alignment with the inner side of said door, said inner end portion having a recess extending into said pin from said inner end surface, said recess having flat side portions to form a socket for insertion of said removable handle when used to actuate said mechanism from the inner side of said door, said mechanism including a car seal arrangement comprising a vertical lug extending outwardly from one of said rods, said lug being spaced from the inner end of said rod, a flange extending from the handle secured to the pivot pin of said cam member, an aperture in said lug and in said flange, said flange being in proximate parallel relation with said lug and said apertures being in horizontal alignment with each other when said door is locked in closed position whereby the car seal is applied through said apertures and such seal may be broken by the shearing action between said flange and said lug when said mechanism is actuated from the inner side of said door.

3. In a laterally movable door of a vehicle door opening having an actuating mechanism for moving said door into and out of said door opening including a rotatable cam member vertically disposed within said door, said cam member having a horizontal pivot pin rotatably mounted on said door, a latch keeper mounted on the framework defining said door opening at one side thereof, a locking device mounted on the outer face of said door for generally linear reciprocation in the keeper in a plane parallel to the face of said door, an opening in said face, a projection on said device extending through said opening for generally linear reciprocation, an outwardly extending lug portion on said cam member having a diagonally extending cam groove engaging said projection and generally linearly moving said locking device to its extended and retracted positions upon rotation of said cam member in respectively opposite directions, said locking device being received by said latch keeper for limiting outward horizontal movement of the door in the closed door position when the latch is in extended position and being provided with biasing means for holding the locking device in retracted position when the door is opened.

4. In an operating mechanism for a laterally movable door including a fixed handle at the outer side of the door and a removable handle at the inner side of the door, said handles being rotatable in a plane parallel to the plane of the door to actuate the mechanism, a seal arrangement comprising a lug extending from said mechanism at the outer side of the door, a flange extending from said fixed handle, and apertures in said lug and said flange respectively, said lug and said flange being in prox-

mate parallel relation with each other and said apertures being in alignment with each other when the door is locked in closed position, a seal applied through said apertures, and said seal being broken by the shearing action between said flange and said lug when said mechanism is actuated from the inner side of said door by rotation of said removable handle.
